(57) **CLAIM**

The ornamental design for a reduced bleed check valve, as shown and described.

DESCRIPTION

FIG. 1 is a top, rear perspective view of a reduced bleed check valve;

FIG. 2 is a top, front perspective view thereof;

FIG. 3 is a side view thereof, and the opposing side is a mirror image thereof;

FIG. 4 is a rear view thereof;

FIG. 5 is a front view thereof;

FIG. 6 is a top view thereof; and,

FIG. 7 is a bottom view thereof.

The broken lines showing unclaimed portions form no part of the claimed design.
